UNITED STATES PATENT OFFICE

GEORGE POSNICK, OF BROOKLYN, NEW YORK

GARMENT-CHECKING SYSTEM

Application filed January 14, 1926. Serial No. 81,349.

This invention relates to improvements in devices for checking garments and other articles. It is particularly designed for use in hotels, club rooms and other similar places where a cloak or check room is provided for checking coats, hats, and other articles. Broadly it comprises operable mechanism, whereby each individual user may place his or her wraps in a cloak or checking room without the assistance of an attendant. The device is intended to be installed in a room that is not accessible to the user. It comprises an endless conveyor which cooperates with an upper and lower trackway or runways along which the garment hanger which supports the article to be checked is moved by the conveyor. Each user is provided with an electric circuit closing key of special construction which, when it is inserted in a switch device adjacent the entrance, a door to the check room, closes a particular circuit to an electromagnet that automatically releases a lever device on which the garment hanger is normally supported and causes this lever device to drop or tilt downward into an inclined position which permits the hanger to roll down this device onto the lower trackway. This operation closes an electric circuit to an electric motor which causes the endless conveyor to be operated and move the garment hanger on the lower trackway to a point which is adjacent to the door opening. The operator now opens the door, which in turn, opens the motor circuit and stops the operation of the conveyor. The user or operator then places the garment on the hanger, and, in the operation of closing the door the motor circuit is again closed and the endless conveyor is again set in operation causing the hanger to be moved along the upper trackway until it is replaced on the lever arm on which it was previously supported; the lever arm, in the mean time, having been automatically tilted from its lowermost to its uppermost position in order to register or be in line with the upper trackway for receiving the hanger therefrom. This lever intercepts the travel of the coat hanger, and, being in an upwardly inclined position, the garment hanger rolls downward thereon to its original position. In this operation the hanger trips a latch which permits the lever to assume its normal or original position. In order to remove the garment the same operations are carried out.

Referring to the drawings:

Fig. 1 is a plan view of the complete apparatus showing four of the garment hangers adjacent their respective magnets, the endless conveyor, the door which is located at one end of the endless conveyor, and trackways.

Fig. 2 is a side elevational view substantially on the line 2—2 of Fig. 1 showing the upper and lower trackways on which the garment hangers travel, the endless conveyor, the four garment hangers, the counter balance weights for tilting the levers when the hangers are removed and the cooperating mechanisms between the door and the adjacent ends of the tracks.

Fig. 3 is an enlarged detail view of the lever mechanism which supports the garment hanger, the full lines showing the normal position and the two dotted lines for conveying the garment hanger onto the lowermost trackway, and, for returning it from the uppermost trackway to its normal position on the lever together with the lever locking latch, the two electric circuit closing positions, and two positions of the hanger.

Fig. 4 is a plan view of Fig. 3 showing the trip magnet, and the locking latch for the lever.

Fig. 5 is a detail view of the electromagnet for releasing the lever arm on which the garment hanger is normally supported.

Fig. 6 is a wiring diagram of the electrical circuits and showing the contacts for opening and closing the circuits to the motor which operates the endless conveyor, the sliding door, the contact lever operated thereby, and four of the levers which supports the garment hangers in full and dotted line positions respectively.

Fig. 7 is a detail plan view of the switch to receive the special keys shown in Figs. 8 to 10, with one of the constructions of which each individual user is supplied for closing the circuit to one only of the electromagnets

which releases a particular tiltable arm which supports that garment hanger.

Fig. 7A is a sectional view on the line 7A—7A of Fig. 7.

5 Figs. 8, 9, and 10 are keys showing different lengths of contact arms.

Fig. 11 is a detail plan view of the latch which cooperates with the tiltable lever for retaining it in the upwardly inclined position, 10 or, to permit it to assume the downwardly inclined position.

Fig. 11A is a side elevational view of Fig. 11.

Fig. 12 is a plan view of the inner end of the 15 tiltable lever, the rod on which it is pivotally supported, the two rollers of the garment hanger. In this view the lever is in its normal position with a hanger thereon.

Fig. 13 is a side elevation of Fig. 12 with 20 the armature latch for retaining the lever in this position.

Fig. 14 is a plan view showing the latch moved to one side for releasing the lever to permit it to assume the downwardly inclined 25 position shown in Fig. 3.

Fig. 15 is a side elevational view of Fig. 14.

Fig. 16 is a plan view of the garment hanger on its return or downward movement from the upper trackway and at the moment of 30 the swinging of the latch on the lever into a position to permit retaining the lever in its upward inclined position and for returning the lever to its normal full line position.

Fig. 17 is a side elevational view of Fig. 16.

35 Fig. 18 is a detail view of a portion of the slidable door, the cooperating lever between the door and the garment hanger for transferring the hanger from the lower trackway onto the upper trackway.

40 Fig. 19 is a side elevational view of Fig. 18 showing the position of the parts when the door is opened and which operation transfers the garment hanger from the lower to the upper trackway.

45 Fig. 20 is a view similar to Fig. 18 but showing the slidable door in its normally closed position with the electric circuit to the motor that operates the endless conveyor closed.

50 Fig. 21 is a side elevational view of Fig. 20 showing the elevated end of the lower track.

Fig. 22 is a view illustrating the door when 55 moved into its open position after the garment hanger has left the lower trackway and is about to be transferred to the upper trackway. This operation opens the circuit to the motor.

Fig. 23 is a side elevational view of Fig. 22 at the moment of transferring the hanger, by 60 the operation of opening the door, to the upper trackway.

Fig. 24 shows the position of the door during 65 its opening movement and just before its return movement and with the hanger trans-

ferring lever about to disengage the trip mechanism on the door.

Fig. 25 is a view similar to Fig. 24 but showing the lever mechanism disengaged from the trip mechanism on the door.

70 Fig. 26 is a view showing a further movement of the door, on its return movement and with the lever on the opposite side of the trip mechanism on the door.

Figs. 27, 28, and 29 are detail views of the 75 trip device which is attached to the inside of the door for operating the levers for transferring the garment hanger.

Fig. 30 is a view showing the garment hanger on the upper trackway and at the 80 moment of being transferred from this trackway to the upwardly inclined tiltable supporting lever as shown in Fig. 3.

Fig. 31 shows the hanger after it has left the upper trackway, and

85 Fig. 32 is a detail perspective view of the stop plate on the end of the tiltable lever.

Referring to the drawings in detail:

1, 2, 3, and 3' designate the two side and end pieces of the apparatus, or in general, the frame work. 4 designates a rod or fixed

90 pivotal bar for supporting the several garment hangers each of which is designated in Fig. 2 by the numeral 5, four for example are shown. 6 designates the lower trackway and

7 the upper trackway along which the garment hangers are moved. These two trackways are supported by the metal hangers 8

95 that are attached to the piece 3'. The pivotal lever device on which each of the garment hangers is normally supported comprises a bar 9 which is pivotally supported on the fixed rod 4. Secured to each bar is a piece of insulation 10 and secured to this piece of

100 insulation is a metal projecting part 11 for engaging and closing the motor circuit contacts at 13 when the lever 9 is in the dotted line position 9² (see Figs. 3 and 6). Attached to the hanger bar 9 is a counter balance weight

105 12. Located immediately above the part 11 are two contacts 14' with which the metal part 11 engages when in the full line position 9.

Located over the end 11 is a latch 14 that carries the contacts 14' that are included in series

110 in the electromagnet circuits (see Fig. 6). This latch is pivotally attached at 15 to the fixed part 2. This latch carries an armature

115 16 which is placed opposite the pole of the electromagnet 17. It is understood that there is an electromagnet for each lever 9. 18 is a fixed stop which is attached to the piece 2

120 and engaged by the part 11 of the lever 9 for limiting its upward movement. Depending from a suitable support over each lever 9 is a bracket 19 on which support is pivotally attached at 21 the stop or latch piece 20 for controlling the movement of the lever 9. 20' is a

125 stop on 19 for limiting the movement of the latch 20. It is formed with a depending portion 22 and an operating arm portion 23. 24

130

100

105

110

115

120

125

is a spring for normally moving the part 22 towards the lever 9 in the position shown in Figs. 1, 12, 13, 14, and 15. This spring operates to normally move the depending portion 22 of the latch over the lever 9, for retaining the lever in the dotted line position 9² to permit the garment hanger to pass from the upper trackway 7 downward into its original normal position (see Fig. 3).

Referring now to the garment hanger proper. 25 is a bar which has attached at its lower end the part 26, and attached to this part are the depending rods 27 and a cross bar 28. Attached to the bar 26 is a garment or coat hanger 29. The upper end of the bar 25 is connected to the piece 30 which is formed with the two offset portions 31 and 32. 33 is a pin which is attached to the side of the offset piece 31. This pin is engaged by the pin 51 on the endless conveyor 39 for elevating the garment hanger. Located on the vertical side of the piece 31 is a grooved roller 34 and located on the offset piece 32 is a grooved roller 35 (see Figs. 3 and 30). The roller 35 engages the upper edge of the garment hanger lever 9 and the roller 34 engages the trackways 6 and 7. Attached to the outer end of the lever 9 is an angular shaped stop plate 36, a detail of which is shown in Fig. 32. The piece 36 is formed with an upwardly extending curved portion 37 and a depending curved portion 38 which is located near the upper trackway 7 shown in Fig. 1. These portions are to permit the arm 31 and roller 34 to pass thereunder (see Figs. 30 and 31) when the hangers rolls down the bar 9 in the position 9² (see Fig. 3).

Referring now to Fig. 2 which illustrates in side elevation the two trackways 6 and 7. 39 designates an endless chain conveyor that is supported on the four sprocket wheels 40, 41, 42, and 43. These wheels are rotatably supported in the hangers 44 and 45.

The endless conveyor is operated from a suitable source of motive power as an electric motor 46 shown in Fig. 6 through a driving belt 47. The lower trackway 6 is formed with a curved and upwardly extending portion 48 and on this portion is located or attached a right angled shaped spring 49 with a freely movable upper horizontal end part 50. 51 are a series of pins which are attached to the endless conveyor at suitable distances apart. These pins are for the purpose of engaging the garment hangers to move it along the trackways 6 and 7.

Pivotedly attached to the upper part 48 of the trackway 6 is an L shaped lever 52 at the point 53. The lower depending arm 54 of this lever is located adjacent the horizontal part 50 of the spring 49, (see Figs. 19, 21, and 23) and the stop arm 55 of the L shaped lever extends over the vertical passageway between the part 48 and the vertical strand 65 of the chain conveyor 39. Pivotedly attached

to the L shaped lever 52 is a link 56, the lower end of which is connected to the lever 57, that is pivotally attached at 58 to a fixed support 59. The lower end of the lever 57 is cutaway or reduced in thickness as indicated at 60. This cutaway end portion is designed to travel in the groove 61 of the cam member 62 on the door when the door is opened, and, along the outer surface 62' when the door is closed (see Figs. 18 to 26) inclusive. 64 is a spring for normally moving the lever 57 towards the door. Attached to the forward end of the cam part 62 is a curved spring or track like portion 65 which is designed to direct the lower end of the lever 57 around and along the outer surface 62' and back into alignment with the groove 61 when the door is closed. These steps are illustrated in Figs. 18 to 25 inclusive. The movement of the door 63 into its closed position operates to lift the garment hanger from its position of rest on the spring arm 50 upward onto the upper track 7. This operation is shown in Fig. 23 wherein the arm 55 disengages the upper surface 31' of the part 31 permitting the garment hanger to be elevated onto the track 7. The stop arm 55 prevents the hanger from being carried by the pin 51 on the chain 39 beyond this point when it comes to rest to permit the user to place the garment on the hanger. Secured to the door 63 is an angular shaped plate 66 which is in the same horizontal line as the lower end of the lever 67, see Figs. 18, 20, 22, 24. This lever is normally actuated toward the plate 66 by the spring 68. Its upper end operates to close the circuit to the contacts 69, which as shown, includes the circuit to the motor 46 by means of the wires 70, 71, the battery 72, and the two contact points 13. It will therefore be seen that when the door 63 is opened or moved in the direction of the arrow 74 that the motor circuit is broken at the contacts 69, which stops the movement of the chain 39 permitting the user to insert his garment through the door opening 75.

It being understood that the garment hanger is now located on the inner end 7' of the upper track 7 (see Fig. 19). The next stop is to move the garment hanger along the upper trackway 7 and onto its particular supporting lever 9. This is accomplished by the operator closing the door 63 which closes the electric circuit to the motor 46, whereby the chain conveyor 39 is again set in motion. One of the pins 51 on the chain now engages the upwardly extending part 31 which moves the garment hanger and the roller 34 along the trackway 7 until the roller 35 strikes or engages the upwardly extending part 36 on the outer end of the lever 9. This causes the roller 35 to be brought into alignment with the lever 9 and as this lever is now in the upwardly inclined position 9², as shown in Fig. 3 due to the weight 12, it permits the hanger to roll downward and tilt the lever into the

70

75

80

90

95

100

105

115

120

125

130

full line position shown in Fig. 3 at 9. This 5 operation breaks the electric circuit at the contact points 13 thus opening the circuit to the motor 46, (see Fig. 6) whereby the operation or travel of the conveyor 39 is brought to a standstill.

In the operation of rolling downward on the lever 9 the forwardly extending part 31 (see Fig. 13) of the garment carrier engages 10 the arm 23 of the pivoted latch 20 and rotates the same into the position shown in Fig. 13 whereby the depending part 22 is moved away from the upper surface of the lever 9 and to one side of the same, shown in Fig. 15. That 15 is to say the depending part 22 is moved from the upper surface of the inner end portion of the lever 9 shown in Fig. 17 to that shown in Fig. 15 whereby the lever 9 automatically assumes the full line position shown at 9 and 20 with the inner metal end 11 directly under the latch 14 which latch, as previously stated, is withdrawn when the electromagnet 17 is energized by the insertion of a key 76 shown 25 in Figs. 8, 9, and 10. The electrical circuit through the several electromagnets 17 is now complete by the metal part 11 engaging the contacts 14'. This key it should be noticed 30 is of special construction, the contact part 77 being of different lengths in the different views, is designed to engage one of the terminals 78 shown in Fig. 7A, whereby a particular key will close the circuit to one of the electromagnets 17 and release one of the hanger levers 9.

Having thus described the various parts and elements of the device, the operation in brief is as follows: Assume that a person wishes to place his garment on one of the hangers 5. He inserts one of the keys shown 40 in Figs. 7A to 10 inclusive in the switch 78 shown in Fig. 7. This closes the circuit to one of the electromagnets 17, through the wire 76', one of the contacts 14', battery 14², and one of the electromagnets 17. The 45 energization of one of these magnets attracts the armature 16 of the switch 14. This releases the garment lever arm 9 and permits it to assume the dotted line position 9' as shown in Fig. 6 and the roller 35 to 50 travel down this lever and onto the lower trackway 6. After the hanger member is located on the track 6 as shown in Fig. 3, the counter balance weight 12 tilts the lever 9 upward into the dotted line position 9², 55 (see Fig. 4). This operation closes the motor circuit at the contact points 13 and operates the conveyor 39 causing a pin 51 on the chain 39 to engage the part 31 of the garment hanger and move it along the lower track 6. The pin 51 engages the pin 33 and lifts the hanger until it snaps by and rests on the part 50 of the spring 49 and below the stop arm 55 of the bell crank lever 52. The operator now opens the door 63. 60 This operation permits the part 66 on the

door to move the lever 67 and break the motor circuit at the contacts 69. This brings the carrier 39 to rest. He now passes the article through the door opening 76 and places it on the hanger 5. This position is shown in Fig. 2. Next he closes the door 63 and in this operation the lower end of the lever 57 operates, through the action of the cam 62 on the door to move the depending arm 54 and remove the garment carrier from the spring 50 onto the upper track 7 (see Fig. 19). In closing the door the motor circuit is again closed at the contacts 69 causing a pin 51 on the endless carrier 39 to engage the garment carrier 5 and move it along the upper track 7 until the roller 35 engages or is intercepted by the upwardly projecting part 36 on the lever 9 when the hanger is transferred onto the lever 9 which, as previously stated, is in the upwardly inclined position 9². It now rolls downward on this lever arm and into the position shown in Fig. 3. This operation causes the movement of the latch 20 which moves the depending arm 22 into a lateral position to permit the lever 9 to swing downward into the full line position 9 thus closing the circuit at the contact again at the points 14'. The metallic end 11 is now located under the lever retaining latch 14.

In order to obtain possession of the articles on the hanger the same operations are repeated, that is to say, the user inserts his key in the switch causing the latch to release the lever 9 and the hanger to move along the lever 9 onto the lower trackway 6, then to be moved by the carrier 39 and onto the arm 50 of the spring 49 into the position shown in dotted lines in Fig. 2. Upon the opening of the door 63, the garment may be removed.

After the door is closed the apparatus is again set in motion and the empty hanger returned to its original position on the lever 9 as shown in Fig. 3. It will therefore be seen that I have provided a garment checking apparatus that is automatic in its operation and one that may be operated without an attendant, to place the articles in the checking room and remove the same therefrom when required. The apparatus also precludes an unauthorized person from obtaining possession of such articles.

What I claim is:

1. In a checking apparatus, the combination with an endless conveyor, an upper and a lower trackway, a series of garment supporting hangers, means for supporting such hangers, means for releasing the said supporting means for permitting the hangers to pass onto the lower trackway, the endless chain operating for moving the series of hangers along the said trackway, a door, means operated when the door is opened to cause the endless conveyor to cease operating and to

again be set in operation when the door is closed, the endless conveyor operating for returning the hangers to their original positions.

2. In combination, in a garment checking apparatus, a garment hanger, a tilttable lever for normally supporting the hanger, electro-mechanical means for releasing the lever to permit it to assume a downwardly inclined position, a track to receive the hanger from the said lever, a second track, means for transferring the hanger from the first to the second track, and means for transferring the hanger from the second track to its original position on the tilttable lever.

3. In combination, a tilttable lever, a garment hanger, means for supporting the hanger on the said lever, means for retaining the lever in a position to prevent the hanger from moving along the same, electromechanical means for releasing the said lever, a counter weight for tilting the lever into an upwardly inclined position, means for transferring the hanger back again onto the said lever, and means operated by the hanger for resetting the tilttable lever.

4. In combination, a tilttable lever, rollers for movably supporting garment hangers thereon, upper and lower trackways, an endless conveyor located adjacent the trackways, electromechanical means for releasing the lever to permit the hanger thereon to pass onto the lower trackway, a counter balance weight on the lever for tilting the same into a position whereby its upper end portion is in registration with the plane of the upper trackway and the lower end of the lever operates to close an electric circuit in which an electric motor is included, for operating the endless conveyor, the upper and lower strands of the conveyor being located adjacent the upper and lower trackways whereby when the conveyor is set in motion by the said operation of the lever, the hanger is moved along one of the trackways by the conveyor and into a position that is opposite a door opening, said door having a part thereon which when the door is operated opens the circuit to the motor, means also operated by the door for transferring the hanger from its position of rest opposite the door to the upper trackway, whereby, on the closure of the door the motor circuit is again closed, and the endless conveyor operates to move the hanger along the upper trackway, and means to intercept the movement of the hanger for transferring it again onto the pivoted lever, and means on the lever actuated by the return movement of the hanger to reset the lever in its normal or original position.

5. A garment checking apparatus comprising in combination, a pivotally mounted hanger supporting lever, a counter balance weight attached to the lever, means for movably supporting the hanger on the lever, an

electromagnet, an armature therefor which is formed with a shoulder portion for retaining the lever in its normal or hanger supporting position, an upper and lower trackway, an electric circuit for closing the circuit to the electromagnet for operating the armature and releasing the lever to permit the counter weight to tilt the lever and the hanger thereon to be transferred to the lower trackway, the counter balance weight operating to tilt the lever into an oppositely inclined position for moving one end of it to register with the upper trackway and its opposite end to close an electric motor circuit, means operated by the motor for moving the hanger along the lower trackway, one end of this trackway being curved upward to the plane of the upper trackway, a spring on the curved portion to receive the hanger for retaining it in a stationary position, a slidable door, a link mechanism between the door and the curved portion of the track whereby when the door is operated the hanger is transferred onto the upper trackway and the circuit to the motor is closed for operating the movable means which transfers the hanger along the upper trackway, and means on the lever for intercepting the hanger for locating it again thereon, and means operated by the hanger on the lever for resetting the lever in its original position.

6. In a garment checking apparatus, the combination, an endless conveyor member, means for operating the same, two trackways a tilttable lever on which a garment hanger is movably supported, means for retaining the said lever in substantially a horizontal position, means for releasing the said lever, means for retaining the lever after being released in a position to permit the hanger to pass from the said lever onto one of the trackways, means for tilting the lever after the hanger has left the same into a position to cooperate with the other trackway, means for transferring the hanger from one trackway to another, and means for returning the hanger again onto the lever.

7. In combination, a tilttable lever for the purpose described, a two armed latch pivotally attached to the same, a counter weight attached to the lever for retaining the lever in an upwardly inclined position when the latch is in one position and for permitting the lever to assume another position when the latch is in another position, a garment hanger movably supported on the lever and so constructed as to move the latch from one position to another.

8. A tilttable lever for the purpose described, a counter weight for the same, a movable garment hanger mounted thereon, one end of the lever having an upwardly inclined plate member for cooperating with a trackway for intercepting a garment hanger when moved along the trackway, a two armed latch

70

75

80

85

90

95

100

105

110

115

120

125

130

pivottally attached to the lever, one arm being in the path of the hanger when moved along the same, the other arm being designed to retain the lever in an upwardly inclined position and to permit the lever to tilt and be moved by the hanger into another position and a counter weight attached to the lever for tilting the same when the hanger is transferred therefrom to another trackway, as described.

10. A garment hanger for the purpose described comprising a depending arm member, a piece attached to the depending part and formed with two offset portions, rollers attached to the upwardly extending part and arranged at an angle to each other, one of the rollers being designed to move along a tilt-able hanger lever and the other roller to move along a trackway that is arranged in a plane 20 that is at an angle to the plane of the bar.

11. A garment checking apparatus having in combination with the wall of an inclosure in which is formed an opening, a slidable door for the opening, a trackway, link mechanism 25 between the trackway and the door, an endless conveyor arranged adjacent the trackway for moving a garment hanger along the trackway, means on the trackway for temporarily supporting the garment hanger, the 30 construction and arrangement being such that when the door is operated, the hanger is automatically transferred from the trackway onto a second trackway, said second trackway being designed to convey the garment hanger to a predetermined position relative thereto and cooperating means for operating the conveyor when the door is closed.

12. In combination a series of electromagnets, a series of tilttable levers each designed 40 to receive a garment hanger, an electric circuit closing switch, electric circuits between the switch, the electromagnets and the levers, contact devices designed to be opened and closed by the levers, means for retaining the levers in a normally closed circuit and in 45 series with each other, a switch key element designed to close the circuit to a particular magnet, means cooperating with said magnet for releasing the lever to permit it to tilt into a downwardly inclined position on which a garment hanger is placed, counter balance means for tilting the lever into an oppositely inclined position after the hanger is removed from the lever, a motor circuit, contacts in the 50 motor circuit arranged in parallel with the terminals of the circuit, whereby when the lever is tilted into the second position, the motor circuit is closed, an endless conveyor operated by the motor when the motor circuit 55 is closed, and means comprising a slidable door, a lever actuated thereby for opening the motor circuit when the door is moved into the open position and for closing the same when moved into a closed position.

65. 12. In a garment checking system, the com-

bination, a trackway which is formed with an upwardly projecting part, an angular shaped spring attached to the said part for temporarily supporting a member which is designed to be moved along the trackway, an elbow lever pivotally attached to the said part, one arm of the lever extending below the upper part of the spring, the other arm being located over the spring, a door, a cam member on the door, links between the cam and the elbow lever, a second trackway adjacent the said part whereby when the door is operated, the member on the spring may be moved therefrom onto a second trackway, as described.

13. In a garment checking system, the combination, an upper and lower trackway, a pivotally mounted lever, an electromagnet, an armature therefor for retaining the lever in one position, a locking latch adjacent the lever for retaining the lever in an inclined position, a part movable on the said lever for operating the latch to permit the lever to assume a different or normal position, and a counter weight attached to the lever for tilting the lever when the latch is operated by the movable part on the lever.

14. In combination, in a garment checking system, an endless conveyor, pins attached thereto, an upper and lower trackway, a hanger designed for movement on the trackways, the lower trackway having an upwardly extending curved end part which terminates adjacent an end of the upper trackway, a pin on the hanger which is engaged by a pin on the conveyor for elevating the hanger at the said curved part, means operated by a door for transferring the hanger from the lower to the upper trackway, and means for transferring the hanger from the upper trackway to a suitable support, as described.

GEORGE POSNICK.
